CORRECTOR FOR CALENDAR CLOCKWORKS

Friedrich Meyer, Grenchen, Switzerland, assignor
to Felsa S. A., Grenchen, Switzerland, a joint-
stock company

Application August 7, 1951, Serial No. 240,622
In Switzerland April 21, 1950

2 Claims. (Cl. 58—58)

1

This invention relates to calendar clocks and watches more especially of the type in which a date member such as a disc is formed with internal toothing in which an annular date member formed with internal toothing is driven by the clockwork.

It is more particularly concerned with a corrector serving for turning the date member independently from the motoric drive in order to adjust or correct it.

The corrector according to this invention has the form of an elastic double-armed lever adapted to be rocked or oscillated, the free end of one of the arms of said lever engaging the inner teeth of the date member.

I prefer forming one of the arms of the double-armed lever as a spring and arranging its center point outside of the date member with one of its arms extending underneath said member.

In the drawings affixed to this specification and forming part thereof an embodiment of this invention is illustrated diagrammatically by way of example.

In the drawings

Fig. 1 is a plan view and

Fig. 2 is a cross-section on the line A—B in Fig. 1.

Referring to the drawings 10 is the annular date member and 20 are some of its internal teeth which I intended to be marked 1—31. This date member is driven in a well-known manner by the motor (clockwork), through a gear 12 rotating at a speed of 1 revolution per day, by means of the driver 13 in such manner as to be imparted every day an angular movement equaling one pitch. Stopping in the position it occupies, is effected by an inner barrier 9/11 consisting of a roller 9 which is forced by a spring 11 into the gap between two teeth of the member 10. Thus the disc or annulus 10 is turned counter to the action of the spring 11.

The corrector proper, i. e. the means enabling the date member to be turned through any desired angle independently of the motor drive, consists of a substantially triangular part 7 which together with the U-shaped part 4 of a spring fixed near one of the corners of the triangle is made integral with this spring. The free end of the spring 4 abuts against the pin 2 fixed to the bottom plate.

The corrector is sunk in an indenture of the plate and held in place by a screw 1 allowing it to be rotated. The triangular part 7 may be considered as a double-armed lever one arm of which (7a) extends from the center point up to the

2

lug 3 which is so bent upwardly that on the double lever being oscillated it will engage the inner toothing 8 of the date member 10. The other arm 7b of the lever, which serves for actuating the lever, extends from the center point to the trigger 5 which is formed by the downwardly bent border portion of the member 7.

This arrangement enables the date member 10 to turn above the corrector which is located in the indenture 14 of the base plate, merely the trigger 5 projecting beyond the circumference of the date member, while on the inner side the lug 3 can be brought to engage with the teeth 8 of the member 10 as above described.

15 In the operation of the corrector, when the trigger 5 is being forced inwards, the arm 7a will be oscillated together with the lug 3 clockwise counter to the action of the spring 4 abutting against the check 2. The lug 3 now meets a tooth of the member 8 and thereby turns the date member through a certain distance which is so chosen that the roller 9 of the inner barrier is just moved across the next following tooth and under the influence of the spring 11 ends the rotation of the date member 10 by one pitch. On the trigger being released, the lever 7a is given by the spring 4 a counter-clockwise return movement, during which it abuts from the inside against the next following tooth and by carrying this tooth along causes the date member to effect a slight rearward movement, of the date member. The dimensions of the parts are so chosen that the rearward rotation of the date member is not sufficient for lifting the roller 9 of the inner barrier across the preceding tooth, so that after the lug 3 has lost contact with the respective tooth, the date member springs back into the position into which it was carried by the actuation of the trigger.

20 In this manner the date member can be advanced through one pitch by pressing on the trigger 5.

Another condition for this sequence of operations is that the resiliency of the spring section 4 is greater by a certain amount than the resiliency of the spring 11, for otherwise the lug 3 on its return movement would not be able to bring about the small return movement of the date member and the corrector would be stuck in its operative position.

The advantages offered by the device according to this invention consists more particularly therein that a large sized date member can be used, because the corrector also acts on the inner teeth which serve for driving the date member.

This is in contrast to the correctors hitherto known which require a separate driving connection or an exterior row of teeth on the date member.

Owing to the mounting of the entire corrector in an indenture of the base plate and to the lack of additional driving parts, a watch provided with the new corrector may be very thin.

I wish it to be understood that I do not desire to be limited to the details shown and described for obvious modifications will occur to a person skilled in the art.

I claim:

1. Corrector for calendar timepieces comprising in combination, a date-indicating ring formed as an internally toothed ring, a rigid corrector lever engaging the inner teeth of said ring, a spring integral with said lever counteracting such engagement of said lever and being arranged outside of the space enclosed by the internal 20 teeth of said ring.

2. The device of claim 1, in which the center point of the lever is arranged outside of the toothed ring, one of its arms extending underneath said ring.

FRIEDRICH MEYER.
